(57) **CLAIM**

The ornamental design for a wind chimes lamp, as shown and described.

DESCRIPTION

FIG. 1 is a perspective view of a wind chimes lamp showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged top plan view of the wind chimes lamp; and,

FIG. 11 is an enlarged bottom plan view of the wind chimes lamp.

The evenly spaced broken lines in the drawings depict portions of the wind chimes lamp that form no part of the claimed design. The long dash-short dash lines surrounding the detail views in FIGS. 1 and 9 are for annotative purposes only and form no part thereof.

1 Claim, 11 Drawing Sheets
